DESIGN FOR A FLOWER CONTAINER OR SIMILAR ARTICLE

Lorraine Smith, Tulsa, Okla.

Application September 3, 1940, Serial No. 94,794

Term of patent 3½ years

To all whom it may concern:

Be it known that I, Lorraine Smith, a citizen of the United States, residing at 622 West Fifth Street, Tulsa, in the county of Tulsa and State of Oklahoma, have invented a new, original, and ornamental Design for Flower Containers or Similar Articles, of which the following is a specification, reference being had to the accompanying drawing, forming part thereof.

The figure is an elevational view of a flower container or similar article, showing my new design.

The appearance of the opposite side of the design is substantially the same as that of the side shown. Furthermore, the figure is substantially flat in end elevation.

I claim:

The ornamental design for a flower container or similar article, substantially as shown and described.

LORRAINE SMITH.
